UNITED STATES PATENT OFFICE.

REGINALD A. FESSENDEN, OF CHESTNUT HILL, MASSACHUSETTS.

BOOK REPRODUCIBLE BY RADIANT ENERGY.

Application filed November 10, 1920. Serial No. 423,186.

My invention relates to methods and apparatus for recording and reproducing language and pictures and the like, and more particularly to recording and reproducing 5 books and moving pictures, and still more particularly to microscopic reproducible records of books, which I call book for the reason that such reproductions are, as will be seen, entirely permanent and durable in 10 contradistinction to the present methods of printing on paper.

The object of my invention is to insure 15 greater efficiency, accuracy, and economy in the production and reproduction of such records and to insure greater durability and convenience in use and the further development of applicant's micro-photographic library system, described in his article in the Electrical World, August 22nd, 1896.

20 Figures 1 to 4 shew, partly diagrammatically, apparatus suitable for carrying out my invention. Fig. 1 shews a view of a disc shaped book, with its page setting projection. Fig. 2 is an edge elevation of a disc 25 shaped book. Fig. 3 shews a view of square book, and Fig. 4 an edge elevation of it. Fig. 5 shews a view of a cylindrical shaped book, and Fig. 6 shews it in section and shews the manner in which it is reproduced by the radiant energy.

In Figures 1 and 2, 11 and 11' are disks 30 of some transparent material, preferably quartz or glass. These disks are preferably ground optically true on both surfaces and may be perfectly flat, though a shoulder, as shown at 14, may be left on one of the disks. The disks are then ground true to approximately one ten-thousandth of an 35 inch around a circumference, though such a high degree of accuracy is not necessary.

If the book to be reproduced is in pages 40 the pages are photographed, either consecutively or by pasting the pages up on a wall and photographing them simultaneously on one of the disks. 12, 12 represent such photographs of two pages.

If it is desired to reproduce the illustrations of the book in colors or to reproduce 45 moving pictures in colors three photographs 50 are made of each page in the well known manner for example as described in the treatises on three colour reproductions by Ives and other writers, and combined in the well known manner on the screen.

In place of photographing the page of 55 the book the manuscript of the author may be photographed direct.

For some purposes, however, the writer prefers to photograph the words just as 60 they come in substantially continuous line— i. e. without breaking them up into pages. It is found that by so doing there is considerable relief to the eye in reading as the eye 65 does not have to reverse at the end of each line as it does in reading words printed in page form. Also, due to the breaking up of the line by the punctuation, for reasons well known to authors, the effect due to longer or shorter sentences, etc. can be much better 70 conveyed than when the matter is paged.

The pages may either be photographed in spiral form, as shown in Fig. 1, and the disk continuously revolved in one direction while shortening the radius, or they may be 75 photographed in line form, as shown in Fig. 3, with an abrupt shift at the end of each line to the next line of pages. They may also be photographed as shown in Figures 5 and 6, on a cylinder with the images arranged as described below.

As regards the reproduction of the pages 80 on the disks, the disks may be coated for moderate magnifications with any ordinary good lantern slide coating. It is preferable, however, to use the old wet plate process as this gives finer definition.

Where the positives are used to read from 85 good results may be obtained by using a green light and this may also be used when the negatives are read from, giving green 90 letters on a black background, or if the film is stained, on any desired color of background.

If the ordinary dry plate or wet plate 95 film is used without further treatment the two disks may simply be cemented together. For this purpose any suitable cement may be used, but in most cases the film itself may be used, the second disk being slid sideways 100 on to the film of the first plate while the film is still moist, thereby excluding all air bubbles, and the book subsequently dried, which results in such firm adhesion between the two disks that they will break before 105 they can be separated.

For some purposes it is preferable that the film should be soaked in formaldehyde, 110 which may be done either before cementing

together or after they are placed together and before they are thoroughly dried. I have found that if the film is so soaked in a solution of silver or bichromate salts that 5 a very pleasing moiré effect is produced in the background by the crystallization out of the salt on drying.

Where especial permanency is desired a method similar to the old method of photographing on china is used, in which the wet plate process is used with a platinum salt, as described in the Encyclopedia Britannica, vol. 18, p. 832; or Abney's or any standard work on platinum processes, and 10 after the photographs have been made and developed on the disk, preferably a quartz disk, the disk is heated up as described in the Encyclopedia Britannica, vol. 16, p. 501; or in treatises dealing with the decoration 15 of pottery or the manufacture of fine scales for microscopic work to such a temperature as will burn off all organic matter in the oxygen of the air, leaving only the platinum image of the letters or pictures reproduced, which platinum image apparently sinks right into the quartz or glass as it 20 cannot be scraped off without scraping off the glass.

The two quartz or glass (of a type resistant to sudden changes of temperature) 30 disks are then placed together and heated up to a point just below that at which the quartz or glass commences to bend, when, as is well known in the art, the two disks 35 will actually unite to form a single piece of glass or quartz around the edges without losing their optical figure to any detectable amount. See for example Parker and Dalladay's paper on this method of cementing 40 below fusion, shewing that the distortion produced is less than one twentieth of a wave length of light, i. e. undetectable; Philosophical Magazine, March 1917. This having been done it will be seen that the result 45 is a disk of quartz about an inch in diameter and one-eighth inch thick which contains in its center a platinum reproduction of the book which has been copied.

Such books are more permanent than the 50 cuneiform bricks of the Assyrians and may be heated red hot and dropped into water without cracking or immersed in the strongest acids or alkalies or oils without injury; in fact can only be destroyed of set purpose 55 by the use of a hammer or similar instrument.

Moreover, they are very convenient as a whole library can be carried in a vest pocket and to utilize them it is only necessary to drop them in a slot to be able to read the book or to obtain about fifteen minutes length of moving pictures.

Moreover it is possible to read the book audibly instead of visually and by projecting 60 the images or elements of the book, ac-

tually to reproduce the spoken language; but the method of doing this is not herein described in detail, or claimed.

Referring to Figures 5 and 6 wherein the two portions 15 and 15' of the book are 70 of cylindrical form, the images are designated by the reference characters 22, 22, and are arranged with variable spacing, the said variable spacing corresponding with and conveying the meaning of the recorded matter. To illustrate, and only for the purpose of illustration, these images may be Braille type. Light from the arc 24 is made direct by the condenser 21 and reflected at right angles by the prism 20 so that the two lines 75 of the dots of the Braille type are projected on the selenium cells 16, 16, thereby increasing their resistance every time the shadow of a Braille dot passes through the selenium cell.

17 is a source of voltage and 18, 18' are commutators in series with the selenium cells 16, 16 and telephone receivers 19, 19. On revolving the cylindrical book 15, 15' the shadows of the dots will sweep over the selenium cells 16, 16 and produce fluctuations in the amount of current flowing through the telephones 19, 19. These fluctuations in current may be read without the use of the commutators 18, 18 but are much more easily 90 read when the commutators 18, 18' are used because the commutator 18 may be made to break up the fluctuations produced by the top line of dots to give a note of 1500 frequencies every time a dot passes, while the commutator 18' may be used to break up fluctuations caused by the Braille dots of the lower line so as to produce a note of 750 frequencies every time a lower dot passes.

In this way every letter produces a unique 95 succession of musical notes which is readily identified by the ear.

These books may be traversed or rotated by any suitable mechanical means, not herein shewn. A suitable means for intermitting 110 said rotation is shewn in Fig. 1, where 40 is a little strip of steel connected to the disc 11 and 19, 19' are the poles of an electromagnet. The exciting coil of the electromagnet 19, 19' is connected in circuit with a selenium cell or similar device, and a battery, so that when a shaded portion of the record on the disc 11, is by the rotation, projected or thrown on the selenium cell, the magnet is excited 115 and the strip 40 attracted and held fast until the circuit of the coil is broken by a push button so as to permit it to be rotated to the next page. This method is not however claimed herein.

By multiply connected records in contradistinction to isolated records, is meant records whose elements form a connected and intelligible chain, as the words of a line, the pages of a book, the pictures of a moving picture, or the tracings of a phonograph rec-

ord. Broadly, a multiply connected record is a consecutively and independently projectible series of elements forming an intelligible whole when projected. By applicant's 5 invention numerous new and important technical effects are obtained, by the projection of these microphotographic images, and by other features of his invention. For example, if a microphotographic image of a 10 page of a book were placed in the field of a microscope and observed in the usual manner, the reader would have to keep his head in one fixed position, which would be painful, and impossible for long. Moreover the 15 amount of light would be insufficient for prolonged reading. Also he could not read a phonographic record audibly, reproducing the speech or music, while this can be done when the record is projected.

20 By the term "book" as used herein is meant multiple connected records of all kinds—i. e. not only a succession of pages relating to the same matter but a succession if images of any other kind, for example, 25 moving pictures or phonograph records or audibly reproducible records of sound and speech, of any convenient type, for example that shewn in applicant's U. S. application Serial Number 358,078, filed Feb. 18th, 1907, 30 or his U. S. application Serial Number 685,699, filed March 23rd, 1912.

What I claim is:

1. A book, comprising a transparent thin plate, having optically plane surfaces and a 35 series of microphotographic images of the elements of said book side by side on one of said optically plane surfaces, and thereby adapted for the projection optically of said microphotographic images in intelligible 40 form, and said book being integrally separate from the optical system of the projection means.
  2. A microphotographic book, reproducible by projection in intelligible form, comprising a thin transparent plate having its 45 surfaces optically plane surfaces, a series of microscopic images of the elements of said book side by side on one of said optically plane surfaces, and a second thin transparent
- plate with its surfaces optically plane surfaces, and sealed to that side of the first said transparent plate on which are the said microphotographic images. 50
3. A microphotographic book, reproducible in intelligible form by optical projection, comprising two thin transparent plates, having their surfaces optically plane surfaces, and having one surface of one plate fused to one surface of the other of said plates, and having between said fused surfaces a series of microphotographic images 55 of the elements of said book.
4. A microphotographic book adapted to be projected optically in intelligible form, comprising a series of microphotographic 60 images of the elements of said book enclosed in a transparent medium and out of contact with the external air, and integral and separate from the projecting system of the projecting means. 65
5. A microphotographic projection book, comprising a series of microphotographic images of the elements of said book and a support for said images, said images being fused into said support. 70
6. A book comprising a transparent plate having optically plane surfaces, and a series of microphotographic images of the elements of said book side by side on one of said optically plane surfaces, said images 75 being variably spaced, and said variable spacing in correspondence with and conveying the meaning of the recorded matter, and thereby adapted for the projection of said micro-photographic images in intelligible 80 form, and integrally separate from the optical system of the projection means.
7. A book comprising a thin transparent plate having optically plane surfaces, and a consecutive and connected and without substantial discontinuity image of the elements of said book side by side on one of said optically plane surfaces, and thereby adapted for the projection of said micro-photographic images in intelligible form, and integrally separate from the optical system 85 of the projection means. 90
